(57) CLAIM

The ornamental design for a cosmetic pad, as shown and described.

DESCRIPTION

FIG. 1 is a perspective view showing our new pad design;
 FIG. 2 is a top plan view;

FIG. 3 is an enlarged cross-sectional view along line 3—3 of FIG. 2;

FIG. 4 is a bottom plan view;

FIG. 5 is a front elevational view;

FIG. 6 is a rear elevational view;

FIG. 7 is a left side elevational view; and,

FIG. 8 is a right side elevational view.

The portions of the cosmetic pad shown in broken lines are for illustrative purposes only and form no part of the claimed design.
